(12) **United States Design Patent**
Miller et al.

(10) **Patent No.:** US D677,438 S
(45) **Date of Patent:** ** Mar. 5, 2013

(54) **BARK CONTROL DEVICE HOUSING**

(75) Inventors: **Channing Miller**, Fort Lauderdale, FL (US); **Michael Scalpato**, Boca Raton, FL (US); **Kim Wah Chung**, Shatin (HK); **Wing-Hung Tang**, Tsuen Wan N.T. (HK)

(73) Assignee: **Sunbeam Products, Inc.**, Boca Raton, FL (US)

(**) Term: **14 Years**

(21) Appl. No.: **29/418,460**

(22) Filed: **Apr. 17, 2012**

Related U.S. Application Data

(62) Division of application No. 29/408,473, filed on Dec. 13, 2011, now Pat. No. Des. 669,232.

(51) **LOC (9) CI. 30-04**

(52) **U.S. CI. D30/152; D30/199; D30/155**
